HAND BAG

Filed April 6, 1925

Inventor

WILLIAM E. FLORY

by
Conrad A. Detrich
his Atty.

UNITED STATES PATENT OFFICE.

WILLIAM E. FLORY, OF BROOKLYN, NEW YORK.

HAND BAG.

Application filed April 6, 1925. Serial No. 21,120.

My invention relates to improvements in hand bags and other analogous receptacles, and the same has for its object more particularly to provide a simple, reliable and convenient container which may be readily opened or closed by the change of position of a member serving as a handle or carrier for the receptacle.

Further, said invention has for its object 10 to provide a device of the character specified consisting essentially of a supporting member or handle portion and a receptacle element having its open edge, in part, fixed to said supporting member or handle portion and, in part, movably attached thereto whereby the mouth of said receptacle may be opened or closed by the tilting of said supporting member or handle portion in one direction or the other.

Further, said invention has for its object 20 to provide a device of the character specified in which the mouth of the receptacle or bag is fixedly secured at one point along its edge to a loop-shaped support or member, and the remaining portions of said edge at the opposite sides of said point of securement are loosely or slidably attached to said support or member whereby to cause the mouth of said receptacle to be opened or closed by 25 the movement of the movable parts thereof from or towards said fixed part.

Further, said invention has for its object 30 to provide a device of the character specified in which the mouth of a flexible or pliable receptacle is immovably held at a point along its edge to an annular or loop-shaped handle member, and the remaining portions of the edge of said mouth, at each side of said fixed portion, slidably mounted upon 35 said annular or loop-shaped handle member whereby when said handle member is inclined or brought into vertical position with the fixed portion of said receptacle lowermost the receptacle will be caused to close, 40 and when said handle is brought into reverse position the receptacle will be caused to open.

Other objects will in part be obvious and in part be pointed out hereinafter.

To the attainment of the aforesaid objects 50 and ends, my invention consists in the novel details of construction, and in the combination, connection and arrangement of parts hereinafter more fully described and then 55 pointed out in the claims.

In the accompanying drawings forming part of this specification:—

Figure 1 is an elevation showing one form of receptacle constructed according to and embodying my said invention; the same 60 being shown in closed position;

Fig. 2 is a perspective view thereof showing the same in open position;

Fig. 3 is a detail sectional view thereof, 65 and

Fig. 4 is a detail view showing a modified construction.

In said drawings, the device is represented as comprising a receptacle or bag 10 which may be made of knitted or textile 70 fabric or any other sufficiently flexible or pliable material, and having its open end or mouth attached to a support or handle 11. The support or handle 11 may be of any convenient form but by preference is made in 75 the form of a circular or elliptical member which will serve as a means for carrying the device from which the receptacle or bag is suspended by members such as loops or rings 12 which loosely engage said support 80 or handle so as to permit of the same sliding freely thereon.

In order to cause the open end or mouth of the bag 10 to open and close by the change of position of the support or handle 85 11, the edge of the bag is fixed at one point with respect to said support or handle by securing one ring 12' to an eye 13 fixedly secured in the underside of the support or handle 11, and leaving the rings 12 along 90 the remaining portions of the edge of said bag 10 arranged to each side of said support or handle 11 free to slide thereon.

By preference the support or handle 11 is made more or less elliptical, and the eye 13 95 located at about the center of one of the shorter bends of said handle 11, in order to insure said handle assuming a position with its longer axis vertical when the bag is suspended from the hand or arm, and causing the open end of the bag to be crowded into the smaller curved end of the handle 11, one half, more or less, of the edge of the open end of the bag falling to each side 100 of the eye 13.

In the modification illustrated at Fig. 4, the eye 13 is replaced by a pair of annular ribs 14, arranged parallel with sufficient space between the same to accommodate and retain a ring 12^a secured to the bag 10 110

against longitudinal movement upon the handle 11^a.

When the handle 11 is held in the hand or suspended from the wrist of the person carrying the bag the rings 12 at the open end of the bag will assume a position at the lower end of the handle 11 to each side of the eye 13, and close the end of the bag. When access to the interior of the bag is desired it merely becomes necessary to grasp the end of the handle opposite to that in which the eye 13 is secured and tilt the same so as to bring the end in which said eye 13 is secured into position to a plane above that in which the upper end of the handle, as illustrated at Fig. 2, whereupon the movable rings 12 on the edge of the bag will ride downwardly upon the opposite sides of the handle 11, as indicated by the arrow 20b, until further movement is restrained by the fixed part 12', and thus cause the mouth of the bag 10 to be distended. To close the bag again it merely becomes necessary to reverse the operation just described.

It is to be noted that where the handle or support 11 is not made in the form of an annulus or endless member, that the ends thereof should be disposed in close proximity to one another, and preferably secured together to prevent any of the rings 12 escaping therebetween.

Having thus described my said invention, what I claim and desire to secure by Letters Patent is:—

1. A device of the character described comprising a receptacle having a flexible upper edge, a supporting member, means for fixedly securing a portion of the upper edge of said receptacle to said member, and means for slidably connecting the remainder of the upper edge of said receptacle to said member at opposite sides of said securing means, substantially as specified.

2. A device of the character described comprising a receptacle formed of yielding material having an open upper end, a sup-

porting member, means for fixedly securing said receptacle at one point along the edge of its open end to said supporting member, and the remaining portions of the edge of said open upper end being slidably connected to said supporting member at each side of said point of fixed securement and freely movable about said supporting member towards and from said point of securement whereby to cause the closing and opening, respectively, of said open upper end by the change of position of said supporting member, substantially as specified.

3. A device of the character described comprising a bag, a supporting member adapted to be held in the hand, means for securing said bag at a point along its upper edge to said member, and rings secured along the upper edge of said bag and slidably connected to said member at opposite sides of the point at which said bag is secured to said member, whereby to permit of the opening and closing of said bag by the tilting of said member upwardly and downwardly, respectively, substantially as specified.

4. A device of the character described comprising a bag, a loop-shaped supporting member serving as a handle or carrier for said bag, a ring member fixed on said loop-shaped supporting member whereby to permit of the securement of said bag, at one point along its edge, to said supporting member, and rings secured at intervals along the edge of said bag at each side of said fixed ring-member; said rings slidably engaging said supporting member whereby to cause said bag to be opened and closed by the tilting of said supporting member upwardly and downwardly, respectively, substantially as specified.

Signed at the city of New York and State of New York, this third day of October, one thousand nine hundred and twenty-five.

WILLIAM E. FLORY.
